UNITED STATES PATENT OFFICE.

LOUIS A. CASGRAIN, OF WINCHESTER, MASSACHUSETTS, ASSIGNOR TO JAMES W. BROOKS, PRINCIPAL TRUSTEE, OF PETERSHAM, AND FRANK F. STANLEY, ASSOCIATE TRUSTEE, OF SWAMPSCOTT, MASSACHUSETTS.

JACK FOR SLUGGING AND NAILING HEELS.

SPECIFICATION forming part of Letters Patent No. 609,874, dated August 30, 1898.

Application filed April 16, 1897. Serial No. 632,466. (No model.)

To all whom it may concern:

Be it known that I, LOUIS A. CASGRAIN, of Winchester, county of Middlesex, State of Massachusetts, have invented an Improvement in Jacks for Slugging and Nailing Heels, of which the following description, in connection with the accompanying drawings, is a specification, like letters on the drawings representing like parts.

Boots and shoes having spring or other heels to be slugged come to the slugging-machine on a last. The holes in the last are frequently considerably worn and sometimes they are not bored true, and consequently when such a last is put on a stationary upright pin of a jack the heel to be slugged cannot be kept in proper relation to the bottom of the nose or presser-plate. I have aimed to produce a jack which may readily adapt itself to any hole in any last found in the boot or shoe.

My improved jack contains a rising-and-falling spring-controlled shank provided with a pivoted last-pin on which the last is placed, the holder for said pin being normally acted upon by a spring which tends to tip the last-pin out of its vertical position in a direction away from the edge-gage, and the operator, grasping in his hand the toe and heel of the shoe, may tip it and the said last-pin more or less toward its vertical position, to thus insure the proper contact of the heel with the nose or foot-plate against which the heel is borne, said nose or foot-plate being either horizontal or somewhat inclined from horizontal position, according to whether or not the slugs or nails are to be driven into a flat or into a bevel surface, as is the case with spring-heels.

The last-pin shown is free to rotate in a holder, shown as a sector-shaped block, free to turn on a pivot between ears of the forked upper end of the shank referred to, said holder having a series of teeth, with which coöperate a toothed locking device, shown as a movable $\square$ -shaped block having teeth and located between the ears of said shank, said block being interposed between said holder and the top of a sleeve rising from the swing-plate of the jack, so that when the shank carrying the last-pin and its holder is pushed down against the action of the spring surrounding it, this

being the case whenever a heel is being slugged or nailed, the said locking device when the shank is depressed, due to pressure applied to the bottom of the last mounted on said last-pin, meets the upper end of said hub or sleeve rising from the swing-plate, and said locking device is arrested, while the shank and holder continue to descend, so that the toothed part of the holder is made to engage the toothed part of the locking device, which effects the positive locking of the said holder and its last-pin in place, so that said pin cannot be further moved during the completion of the driving of that nail; but the operator may, if the demands of the work require it, somewhat tip the shoe and the last-pin after the nail has been driven and while the shoe is being fed, the feeding devices then acting to feed the shoe on the horn, the upward pressure of which is at such time released in usual manner.

Figure 1, in elevation, shows a sufficient portion of a nailing-machine with my improvements added to enable my invention to be understood, the last-pin being supposed to be in its lowest position; Fig. 2, a side elevation of the devices shown in Fig. 1; Fig. 3, a detail showing the holder for the last-pin and the shank and swing-plate in section. Fig. 4 shows the last-pin as it will appear in its highest position and free from any pressure. Fig. 5 shows the shank detached. Fig. 6 is a top or plan view of the parts shown in Fig. 2 with the last removed, and Fig. 7 shows the locking device detached.

In the drawings let A³ represent part of a rigid extension from the column of a nailing-machine of usual construction—as, for instance, as shown by like letter in United States Patent No. 490,625, dated January 24, 1893. This extension receives on it a post A⁴, on the upper end of which I clamp by a screw *a* the split sleeve-like shank *a'* of a bed-plate *a²*, having at one side an arm *a³*, provided with stops *a⁴*, the said arm receiving, as shown, a stud-screw *a⁵*, over which is fitted a slotted arm *b* of swing-plate *b'*, resting on the plate *a²* and free to slide and be moved about on said plate as the heel of the boot or shoe is being presented under the driver of 100

the nailing-machine with which the jack is to be used. The swing-plate has an upright tubular hub b^2 , in which and through a spring c , resting on a shoulder b^3 of the hub, is entered the shank-piece c' , enlarged and bifurcated at its upper end to leave ears c^2 . The stops a^4 control the extent of the lateral swinging of the plate b' , while a stud-screw a^5 serves as a guide for the arm b of said plate, and instead of the particular guide shown I may use any well-known equivalent devices.

The shank has a spline c^3 , which enters a groove inside the hub and which prevents the shank from rotating in the hub, but lets it rise freely under the action of said spring c , as in Fig. 4, a washer c^4 , screwed to the lower end of said shank, acting as a stop to limit the ascent of the shank.

Between the ears C^2 , I place the toothed $\square$ -shaped locking device d , it embracing by its legs the portion c^6 of the shank. The ears c^2 receive a suitable pivot, (shown as a stud-screw d^2 ,) tapped at one end and entered by a screw d^3 . (See Fig. 2.) This stud serves as a pivot for the holder e , which carries the freely-rotatable last-pin e' , it entering a hole in the holder, (see Figs. 3 and 4,) where it is provided with an annular groove, in which enters the end of a screw e^2 .

The shank has a connected spring c^3 , held in place by suitable screws e^4 , said spring normally acting to tip the last-pin over from a vertical line, as in Fig. 4.

I have herein shown a shoe f , having a spring-heel f' , mounted on a last f^2 . This last has a hole in its crown, which is fitted over the last-pin, and this done the operator, engaging the toe and heel of the last by his hands, turns the holder and last-pin up far enough to put the bottom of the heel end of the sole properly under the usual nose or foot-plate, (not shown,) and in putting this shoe in place the pressure on the sole is sufficient to depress the last-pin and the shank far enough to cause the toothed lower convexed edge of the holder e to enter the concaved toothed part of the locking device d , and thereafter during the time that the slugs or nails are being driven into the heel the inclination of the last will be preserved.

This my invention is applicable for use in driving slugs or nails into heels of any usual or desired shape, and by tipping the last-pin the inclination to which the slugs or nails may be driven into the heel may be varied to suit the demands of the particular heel being slugged or nailed.

The under side of the swing-plate (but it may equally well be the upper side of the bed-plate) is provided with a series of grooves or spaces to break up the otherwise smooth plain surfaces which would be exposed for contact, such breaking up of the said smooth

surfaces doing substantially away with the friction between the said plates. 65

Having fully described my invention, what I claim as new, and desire to secure by Letters Patent, is—

1. In a jack for holding a boot or shoe when the heel is having fastenings driven into it, a swing-plate, and a vertically-movable shank carried thereby, said shank having a pivoted holder provided with a last-pin, substantially as described. 70

2. In a jack, a shank, a guide for said shank, a spring to support said shank, and a pivoted toothed holder provided with a last-pin; combined with a toothed locking device interposed between said shank and said toothed holder, said locking device engaging 80 said holder when said shank is depressed, substantially as described.

3. A swing-plate having a tubular hub, means to support said swing-plate, a shank having a forked upper end, a spring interposed between the said forked upper end and said hub and normally acting to keep said shank elevated, means to limit the upward movement of said shank under the action of said spring, combined with a pivoted holder 90 having a last-pin, and a locking device arranged to be engaged with said holder to lock the same when the holder and its shank are depressed due to pressure applied to the bottom of the last supported on said last-pin, substantially as described. 95

4. In a jack, a shank, a guide for said shank, a spring to support said shank, and a pivoted toothed holder provided with a last-pin, and a spring to act on said holder to normally tip it and its last-pin out of vertical position; combined with a toothed locking device interposed between said shank and said toothed holder, said locking device engaging said holder when said shank is depressed, substantially as described. 100

5. The plate a^2 having stops and a suitable guide, combined with a swing-plate having an arm coöperating with said guide, a shank fitted in said swing-plate, and a pivoted 110 holder mounted in said shank and provided with a last-pin, substantially as described.

6. The plate a^2 having a stud-screw a^5 and a swing-plate resting on said plate a^2 , and having a slotted arm embracing and free to 115 slide on said stud-screw, combined with a shank fitted into said swing-plate and provided with a pivoted last-pin, substantially as described.

In testimony whereof I have signed my 120 name to this specification in the presence of two subscribing witnesses.

LOUIS A. CASGRAIN.
